UNITED STATES PATENT OFFICE.

ALBERT A. SCHRADER, OF CAPE GIRARDEAU, MISSOURI.

GAME APPARATUS.

1,216,850.

Specification of Letters Patent. Patented Feb. 20, 1917.

Application filed August 11, 1915. Serial No. 44,969.

To all whom it may concern:

Be it known that I, ALBERT A. SCHRADER, a citizen of the United States, residing at Cape Girardeau, in the county of Cape Girardeau and State of Missouri, have invented certain new and useful Improvements in Game Apparatus, of which the following is a specification.

This invention relates to a game apparatus and more particularly to a device for shaking or tumbling dice.

As a principal object, it is contemplated by this invention to produce a dice shaking machine in which the dice shall be shaken and thrown in the full sight of the players or participants of a game, without necessitating, or permitting, either of the players to touch the dice.

It is a further object of this invention to combine in a game apparatus a variety of dice, the sides of which are colored in a corresponding manner, together with a machine for tumbling the dice so as to expose various colored sides thereof throughout the progress of the game.

More specifically, it is an object of this invention to provide an inclosed casing communicating with a visible, yet inclosed compartment, to mount a platform for reciprocation within the casing and to provide means to control the movement of the platform so that dice placed thereon will be shaken or tumbled within the visible compartment.

The above and additional objects which will become apparent as this explanatory description proceeds, are accomplished by such means as are illustrated in the accompanying drawings, described in the following specification and then more particularly pointed out in the claims which are appended hereto and form a part of this application.

With reference to the drawings, wherein there is illustrated the preferred embodiment of this invention, as it is reduced to practice, and throughout the several views of which like characters of reference designate similar parts:

Figure 1 is an end view of the dice shaking machine of this invention;

Fig. 2 is a vertical sectional view therethrough, showing the bottom of the machine casing removed;

Fig. 3 is a horizontal sectional view

through the dice compartment on the line 3—3 of Fig. 1;

Fig. 4 is a similar view through the casing on the line 4—4 of Fig. 2;

Fig. 5 is a detail of the means for actuating the dice platform, and

Fig. 6 is a detail of a die which is preferably used in conjunction with my apparatus.

The dice machine includes, as already explained, a casing 10 and a visible compartment 11 communicating therewith, together with a platform 12 reciprocable between the compartment and the casing for the tumbling or shaking of dice 13. The walls of the casing 10, which are shown as rectangular in arrangement although not necessarily so are preferably constructed from a suitable metal pressed into the desired shape, one of the end walls being formed with a slot 14 for the reciprocation of the actuating handle 15 for the platform. At their base the casing walls are surrounded on three sides by a beading 16 of semi-circular cross section, with convex outer surface as denoted at 17. A slideable bottom 18 closes the under side of the casing 10, three edges of which are receivable within and guided by the beading 16; the other or fourth edge carries a strip 19 similar exteriorly to the beading 16 and forming the base finish on the fourth side of the casing. The strip 19 is rolled about a wire 20 and secured thereto, the ends of the wire being turned at right angles to the intermediate portion and for a suitable distance lie parallel with the sides of the closure 18. These ends are adapted to enter the beading 16 at the sides of the casing, and fitting snugly therein hold the bottom in place. A metal plate 21 is attached to the strip 19 and projects horizontally therefrom to serve as a handle for manipulating the bottom 18. A similar plate 22 is fastened to the beading 16 on the opposite side for symmetry of appearance.

The compartment 11 is mounted upon the casing 10 through the medium of an angular S-shaped supporting strip 23 which is adapted to receive the upper edges of the walls of the casing 10 between a pair of its own doubled edges. The remaining angular bight or channel of the S-shaped strips support the sides and end walls 24 of the compartment, such walls being preferably of glass or a similar transparent material.

105
110
115

Spaced corner strips 25 join the abutting edges of the glass walls 24 while a U-shaped rim piece 26 extends around the upper edges of such walls.

5 The rim strip for one of the end walls 24 carries the curled hinged strap 27 for the reception of the hinge pintle 28 of a swinging closure for the compartment which includes the glass panel 29 suitably supported 10 through the medium of angle strips 30 secured to the undersurface of the inclosing frame 31 surrounding the edges of the glass panel 29. The frame has a downwardly turned forward edge or lip 32 that makes 15 tight frictional engagement with the front edge of the compartment structure when closed.

The platform 12 is of such size as to be freely reciprocable between the compartment 11 and the casing 10, as defined by the 20 inner line of the S-shaped strip 23 which supports the compartment walls. This platform is preferably covered with a cloth 33 which not only adds to the appearance of the 25 machine but also serves to deaden any clatter of the dice 13 as they are tumbled upon the platform. Secured to the center of the platform 12 is the hollow plunger 34 which rides snugly in a similarly constructed casing 35, this latter being supported rigidly 30 within the casing through the medium of spiders 36. This casing 35 is formed with slots 37 through which projects a pin 38 which extends through the hollow plunger 34. Between this pin and a pin 39 similarly 35 arranged at the bottom of the case 35, there is interposed the expansible coiled spring 40, which naturally tends to force the platform 12 upwardly after it has been placed 40 under tension and released.

The actuating handle previously denoted as a whole for the numeral 15 includes a pair of metallic strips 41 which are bent to oppositely pass the casing 35 and continuing 45 therebeyond are pivotally connected to the lateral extensions 42 of a hinge clip 43 secured to the wall of the casing 10. The opposite extremities of the joined strips 41 carry a press plate 44 and the lower edges 50 of the strips are adapted to contact with the upper spring pin 38 in the manner shown clearly in Fig. 2.

The dice preferably employed in connection with the machine described in the foregoing are desirably provided with colored faces, although it will be obvious that any form of dice such as those employing the usual numerical pips may be utilized and to advantage. The dice are placed upon the 55 platform 12 and the handle 15 is then smartly depressed and released, whence the 60 spring 40 in expanding will force the plun-

ger 34 and with it the platform 12 so sharply upward as to thoroughly tumble and shake the dice 13. It will be obvious that a 65 game may be played with these dice without the necessity for any of the participants touching or in any manner handling the dice, thus rendering it certain that no tricks of replacing the dice with ones fraudulently 70 weighted can be attempted, although the dice are always open to inspection by the simple expedient of lifting the cover 29.

While in the foregoing, however, there has 75 thus been illustrated in the drawings and described in the specification such combination and arrangement of elements as constitute the preferred embodiment of this invention, it is desired to emphasize the fact that such minor changes in the matters of 80 proportion and degree may be made in later adaptations of this device as shall not alter the spirit of the invention as defined in the appended claims.

What is claimed is:—

1. A game apparatus of the type described comprising a casing forming a base, a compartment above the casing having transparent walls and a transparent cover, a strip at the top of said casing and surrounding the same having an upwardly open channel to receive panes of glass that form the sides of the receptacle, a folded strip extending over the upper edge of said glass panes, and an open frame containing a glass panel pivoted to one side of the receptacle and adapted to frictionally engage the opposite side, a platform at the junction of said casing and receptacle, and means within the casing for imparting vertical movement to 100 said platform.

2. A game apparatus of the type described comprising a closed casing forming the base thereof made of pressed sheet metal, a strip of sheet metal of S shape cross section mounted upon the top of said casing and extending around the several sides, transparent panels supported at their lower edges by said strip and connected at their vertical edges to form a closed receptacle, a closure for said receptacle comprising a frame and a transparent panel, a platform at the junction of said casing and said receptacle, and means for imparting vertical movement to 105 said platform inclosed within said casing and projecting outwardly through a slot in the sides thereof.

In testimony whereof I affix my signature in presence of two witnesses.

ALBERT A. SCHRADER.
